Mount Pleasant, Tex.

Application June 26, 1941, Serial No. 399,880

3 Claims.

(Cl. 107—28)

This invention relates to a novel dispenser, and more particularly to a dispenser adapted for use for dispensing pancake batter onto a griddle.

It is a primary aim of the invention to provide a sanitary batter dispenser having a manually actuated valve for opening and closing one or a number of discharge ports in the bottom of a batter container or hopper for releasing a quantity of batter and to permit the batter to drop by gravity onto a griddle above which the dispenser is disposed.

A further aim of the invention is to provide a dispenser having the sliding valve so constructed that it can be moved to a position for permitting like quantities of batter to be simultaneously discharged from a plurality of outlet ports of a hopper or container to form pancakes of uniform size, said valve being also arranged to permit batter to be discharged from only one of the discharge passages, if desired.

Still a further aim of the invention is to provide spring pressed supporting means for frictionally holding the sliding valve in engagement with the discharge ports of the hopper or container to prevent leakage of the batter when the valve is in a closed position.

Still another aim of the invention is to provide abutment means for limiting the extent of movement of the valve in either of two directions, said abutment means being so arranged that one or a plurality of the discharge ports of the container will be fully exposed when the valve has reached its extent of movement in one or the other direction in which it is moved.

Other objects and advantages of the invention will hereinafter become more fully apparent from the following description of the drawings, which illustrate a preferred embodiment of the invention, and wherein:

Figure 1 is an end view, partly in section and partly in elevation of the dispenser.

Figure 2 is a bottom plan view of the same taken substantially along the plane of the line 2—2 of Figure 1.

Figure 3 is a longitudinal vertical sectional view taken substantially along the plane of the line 3—3 of Figure 2.

Figure 4 is an enlarged fragmentary transverse vertical sectional view of the dispenser, taken substantially along a plane indicated by the line 4—4 of Figure 3.

Figure 5 is a similar view taken substantially along a plane indicated by the line 5—5 of Figure 3, and

Figure 6 is an enlarged longitudinal vertical sectional view taken substantially along the plane of the line 6—6 of Figure 1.

Referring more particularly to the drawings, wherein like reference characters designate like

or corresponding parts throughout the different views, 10 designates generally the batter dispenser in its entirety and which includes a container or hopper 11 which is provided with depending supporting legs 12. The container 11 is provided with an open top and with outwardly projecting flanges 13 at opposite sides of said open top. The container 11 is provided with a lid 14 having opposite side edges which are bent downwardly and inwardly to form the portions 15 which are adapted to slidably engage the flanges 13 for detachably connecting the lid 14 to the container 11, and to prevent the lid 14 from being removed by an upward movement 15 relatively to the container 11. Lid 14 is provided with a stop 16 at one end thereof to prevent the lid from being moved, relatively to the container 11, in one direction past a closed position. Lid 14 is provided with a handle 17 which is adapted 20 to be grasped for applying or removing the lid, and which is also adapted to be grasped for manually supporting the dispenser 10, as for example, over a griddle, not shown. The container 11, as best seen in Figure 4, is provided with a substantially flat bottom 18. The side walls of the container 11 preferably have inwardly converging lower portions 19. The bottom 18 is provided with a plurality of depending discharge ports 20. In the embodiment of the invention as disclosed, 25 two of the discharge ports 20 are provided which are arranged in longitudinal alinement. A plurality of brackets 21 are fastened to the underside of the bottom 18. Each of the brackets 21 is provided with a downwardly offset inner end 30 through which extends an upwardly projecting set screw 22. The brackets 21 support a supporting frame 23 which includes a substantially flat base portion 24 which is disposed against the underside of the bottom 18 and which has portions 35 which rest on the set screws 22. Set screws 22 are adapted to be advanced for detachably clamping the base 24 against the bottom 18. Base 24 is provided with recessed ends through which project the discharge passages 20, and said recessed 40 ends are each provided with a pair of depending U-shaped hangers 25. A follower plate 26 is disposed within each of the pairs of hangers 25. Said follower plates 26 are each provided with two depending studs 27 which are swivelly connected at their upper ends by the plates 26 and which are provided at their lower ends with restricted threaded shanks 28 which extend through enlarged openings 29 in the bottom or intermediate portions of the U-shaped hangers 25. Cap nuts 30 are detachably connected to the shank ends 28, as best seen in Figure 5. An expansion coil spring 31 is mounted on each of the studs 27 and is disposed between the intermediate 45 portion of a U-shaped hanger 25 and an

end of a follower plate 26 so that each of the follower plates 26 is urged upwardly by means of a pair of expansion springs 31. Each of the expansion springs 31 is enclosed in a resilient sleeve 32. The ends of the sleeves 32 bear against the intermediate portions of the hangers 25 and the undersides of the follower plates 26. Each follower plate 26 is provided with an enlarged opening 33 which is disposed beneath a discharge passage 20 and which is substantially larger in diameter than the bore thereof.

An elongated plate 34 is disposed beneath the bottom 18 and has its ends resting upon the follower plates 26 and yieldably supported thereby in frictional engagement with the lower ends of the discharge passages 20. The plate 34 is provided near one end thereof with an opening 35 and an opening 36, which openings are arranged in longitudinal alignment and in spaced relationship relatively to one another. Plate 34, 20 adjacent its opposite end is provided with a single opening 35, and at said last mentioned end of the plate 34 is provided a perpendicularly disposed stop member 37 which is attached to or formed integral with said end of the plate 34. 25 An arm 38 is secured to and projects outwardly from the corresponding end of the container 11 and is provided with a depending free end 39 which is disposed in the path of the movement of the stop 37. The hanger 25, disposed adjacent the stop 37, is also located in the path thereof so that said hanger and the end 39 form abutments for the stop 37, for a purpose which will hereinafter become apparent.

Plate 34, intermediate of its ends, is provided with a longitudinally disposed row of openings forming a rack 40.

The base 24, intermediate of its ends, is provided with depending ears 41, at the side edges thereof, which are provided with aligned openings, 40 forming bearings, for journaling a shaft 42 which extends therethrough. The shaft 42 is prevented from sliding relatively to the ears 41 by means of collars 43 which are keyed to the shaft 42 and which engage the outer sides of the ears 41. An interrupted gear or pinion 44 is keyed to the intermediate portion of the shaft 42 and is disposed so that the teeth thereof are arranged to mesh with the rack 40, and as seen in Figure 3, the rack 40 is provided with the same number of openings as the gear 44 has teeth. To one end of the shaft 42 is keyed a thumb knob 45 by means of which the shaft 42 is adapted to be manually revolved in either direction for reciprocating the plate 34 relatively to the discharge passages 20.

From the foregoing it will be seen that by turning the knob 45 to turn the shaft 42 and the pinion 44 in a counterclockwise direction, as seen in Figure 3, the plate 34 can be moved to the left, from its position of Figure 3 until the stop 37 abuts against the hanger 25, disposed adjacent thereto. When this occurs the openings 35 will each register with the bore of an outlet passage 20 to permit corresponding amounts of batter 65 to be discharged from the passages 20 and onto a griddle disposed therebeneath to form pancakes of uniform sizes. By returning the plate 34 to an intermediate position, as seen in Figure 3, by rotation of the shaft 42 in the opposite direction, both passages 20 will be closed to pre-

vent escape of the batter, not shown, therethrough. If it is desired to discharge batter for a single pancake, this can be accomplished by continuing the clockwise rotation of the shaft 42 until the stop 37 abuts against the end 39 of the arm 38, at which time the opening 36 will register with the passage 20, adjacent to which it is disposed, for permitting the batter for a single cake to be discharged from the container 11. It will thus be seen that batter for either one or two cakes may be discharged, as desired. Obviously, the container 11 could be enlarged and provided with additional openings 20, and the plate 34, which forms a valve, could then be provided with additional openings 35 and 36 to function in conjunction with the additional discharge passages 20 which are provided. Likewise, if desired, a plurality of valve plates 34 could be provided, in which case the shaft 42 could be provided with a plurality of pinions 44 or more than one shaft 42 could be provided, if desired.

Various other modifications and changes are contemplated and may obviously be resorted to, provided they fall within the spirit and scope of the invention as hereinafter defined by the appended claims, as only one embodiment of the invention has been disclosed.

We claim as our invention:

1. A pancake batter dispenser comprising a container for batter having a plurality of depending outlet passages in the bottom thereof, means for supporting the container in an elevated position, a frame detachably mounted on the underside of said container, said frame having depending hangers at the ends thereof, an elongated plate disposed beneath the container, spring pressed follower means supported by said hangers for yieldably supporting said plate in frictional engagement with the lower ends of said outlet passages, said plate being provided with longitudinally spaced openings, and manually operated means supported by said frame for reciprocating the plate for moving its openings into and out of registry with said outlet passages.

2. A batter dispenser as in claim 1, comprising abutment means for limiting the extent of the sliding movement of said plate, said abutment means being so arranged that each of the outlet passages will be exposed when the plate has reached the limit of its movement in one direction, and so that one of the outlet passages only will be exposed when the plate has reached its limit of movement in the opposite direction.

3. A dispenser for pancake batter and the like comprising a portable hopper, for containing the batter, provided with a discharge conduit in the bottom thereof, a frame detachably mounted beneath the hopper, a reciprocating valve disposed beneath said hopper and supported by the frame, means, forming a part of the frame, for yieldably holding said valve in frictional engagement with the outlet end of said discharge conduit, said valve being provided with an opening, and manually actuated means for reciprocating said valve relatively to said discharge conduit for moving said opening into and out of registry therewith.
